UNITED STATES PATENT OFFICE.

JOHN ROBERT ROBERTSON, OF NEW GLASGOW, NOVA SCOTIA, CANADA.

LIFTING JACK FOR AUTOMOBILES.

Application filed November 7, 1922. Serial No. 599,554.

To all whom it may concern:

Be it known that I, JOHN ROBERT ROBERTSON, a subject of the King of Great Britain, and a resident of New Glasgow, in the Province of Nova Scotia and Dominion of Canada, have invented certain new and useful Improvements in Lifting Jacks for Automobiles, of which the following is a specification.

This invention relates to improvements in lifting jacks for automobiles, and the objects of the invention are to provide a lifting jack which will have, in combination with a universal joint, an exceptionally long lift.

Further objects are to provide a lifting jack with an internal screw nonrotatable and an external rotatable screw operated by a worm gear, in turn through universal joint means operated by a speed wrench.

With these and other objects in view, the invention consists essentially in the novel arrangement and construction of parts hereinafter described in the specification and illustrated by the accompanying drawings that form part of the same.

Referring to the drawings, in which like characters of reference indicate corresponding parts in each figure, and in which:

Figure 1 is a side elevation of my invention.

Figure 2 is a vertical section.

Figure 3 is a section on the line 3—3, of Figure 2.

Figure 4 is a plan view of a speed wrench for operating the jack and also for turning nuts.

In the drawings;

A is the lifting jack comprising a main or principal casting 10, provided with a suitable cap 12, screw secured in place and adapted to shelter a gear hereinafter more fully referred to. Within the casting 10 is an outer left-hand screw 14, provided with two key seats, full lengths, while 15 is an inner right-hand screw provided with a central rod 16 having a suitable key and adapted to fit a pin 11. 17 is an octagon nut slidably engaging with the casting 10 and riveted to the rod 16.

18 is a worm provided with an operating spindle or shaft 19 and designed to mesh with a gear 20 keyed to the outer screw 14 at 21. 22 is the apertured end of the spindle 19 designed to form one member of a universal joint of which 23 and 24 are the

other members connecting the spindle 19 with a tubular member 25 formed with a sleeve 26 on the end, fitted to a hexagon rod 27 designed to telescope with the tubular member 25. 28 is a hexagon fixedly secured on the rod 27 by means of a pin 29 to prevent the rod 27 from turning. The hexagon 28 is adapted to engage with the socket end 30 of a wrench B shown in Figure 4. 13 is a rest pivot on the inner screw 15 adapted to engage with and support the axle of a car or vehicle.

From the foregoing, the operation of my invention can be readily understood, and is as follows: Place the jack under the car, pull out the extension handle to the length required, the universal joint permitting one to stand at almost any angle. Then place the wrench on the end 29 and operate. As the wrench is turned, the worm 18 operates the gear 20, which turns the screw 14, and, as the screw 15 is held from turning by the rod 16 and nut 17, an upward motion of both screws is secured.

It will therefore be seen that I have invented a jack of simple and economic construction which, in combination with the universal joint and a telescopic handle, can be operated at any required angle without the necessity of stopping or otherwise inconveniencing the operator.

It will also be noted that in my jack, the outside is the driver or rotating screw, and that the inner screw is fixed, as far as rotatable motion is concerned, being held by a rod or octagon nut, and the movement of this screw thus confined to an up and down one.

As many changes could be made in the above construction and many apparently widely different embodiments of my invention, within the scope of the claims, constructed without departing from the spirit or scope thereof, it is intended that all matter contained in the accompanying specification and drawings shall be interpreted as illustrative and not in a limiting sense.

What I claim as my invention is:

1. A lifting jack for automobiles, and the like, comprising an inwardly threaded casing, a screw adapted to engage with said casing and threaded on the inside to engage with an oppositely threaded inner screw, a concentrically arranged rod adapted to slidably engage with the inner screw and fixedly secured to the casing, whereby the

rotation of the inner screw is prevented, means carried by the inner screw adapted to support the axle of a vehicle, and means for operating the outer screw to raise and 5 lower the inner screw, and comprising the spline gear keyed to said outer screw and designed to slidably engage with the outer screw, a worm gear meshing with the spline gear, and a spindle for the worm gear, connected through a universal joint at its outer 10 end with telescopic handle means to operate the lifting jack from a distance.

2. A lifting jack of the character described, comprising a suitably threaded casing, a pair of oppositely threaded screw 15 members arranged one within the other and adapted to engage with said casing, a rod for said members adapted to slidably engage with the inner screw, means for operating the screw members to raise or lower the inner screw, axle supporting means carried by the inner screw, said operating means comprising spline gear and shaft means adapted through universal joints means and a telescopic handle to be operated from a distance.

In witness whereof I have hereunto set my hand in the presence of two witnesses.

JOHN ROBERT ROBERTSON.

Witnesses:

IRENE L. MARSHALL,
JOHN ORULL.
